UNITED STATES PATENT OFFICE

158,486

BOTTLE CAP OR THE LIKE

Walter P. Margulies, New York, N. Y., assignor, by mesne assignments, to The Grove Laboratories,
Inc., St. Louis, Mo., a corporation of Delaware

Application July 3, 1948, Serial No. 147,362

Term of patent 14 years

(Cl. D58—26)

To all whom it may concern:

Be it known that I, Walter P. Margulies, a citizen of the United States, and a resident of New York, in the county of New York and State of New York, have invented a new, original, and ornamental Design for a Bottle Cap or the like, of which the following is a specification, reference being had to the accompanying drawing, forming part thereof.

Fig. 1 is a top plan view of the cap or the like showing my new design.

Fig. 2 is a side elevational view of the cap, and

Fig. 3 is a sectional view taken on line 3—3 of Fig. 1.

I claim:

The ornamental design for a bottle cap or the like, substantially as shown.

WALTER P. MARGULIES.
